(57) CLAIM

I claim the ornamental design for a condiment package, as shown and described.

DESCRIPTION

FIG. 1 is a top perspective view of a condiment package, showing the new design.

FIG. 2 is a bottom perspective view thereof.

FIG. 3 is a right side view thereof.

FIG. 4 is a left side view thereof.

FIG. 5 is a rear view thereof.

FIG. 6 is a front view thereof.

FIG. 7 is a top view thereof.

FIG. 8 is a bottom view thereof.

FIG. 9 is a perspective view of an alternative embodiment of a condiment package.

FIG. 10 is a bottom perspective view thereof.

FIG. 11 is a right side view thereof.

FIG. 12 is a left side view thereof.

FIG. 13 is a rear view thereof.

FIG. 14 is a front view thereof.

FIG. 15 is a top view thereof; and,

FIG. 16 is a bottom view thereof.

1 Claim, 8 Drawing Sheets
